H. T. EMERY.

ASH SEPARATOR.

APPLICATION FILED MAY 29, 1920.

1,391,178.

Patented Sept. 20, 1921.

UNITED STATES PATENT OFFICE.

HARRY T. EMERY, OF NORWOOD, OHIO, ASSIGNOR OF ONE-HALF TO MILLER OUTCALT DURE, OF NORWOOD, OHIO.

ASH-SEPARATOR.

1,391,178.

Specification of Letters Patent. Patented Sept. 20, 1921.

Application filed May 29, 1920. Serial No. 385,345.

To all whom it may concern:

Be it known that I, HARRY T. EMERY, a citizen of the United States, and resident of Norwood, in the county of Hamilton and 5 State of Ohio, have invented certain new and useful Improvements in Ash-Separators, of which the following is a full, clear, and exact description, reference being had to the accompanying drawings, forming a part 10 of this specification.

My invention relates to a device for sifting, separating and removing ashes from a furnace or stove.

The ashes shaken through the grate bars 15 of a furnace or stove, by reason of imperfect combustion, normally contain a large amount of unburnt cinders, which if separated from the ashes themselves, may be thrown back into the furnace and provide 20 suitable fuel therefor. The principal object of the present invention is to provide simple means for separating such cinders from the ashes, and whereby the operation may be performed inside the ash pit of the furnace 25 or stove, thus preventing the dust and dirt from being distributed about the cellar or other furnace room.

A further object of the invention is to provide means whereby the sifting operation 30 is performed coincidentally with the agitation of the grate bars of the furnace for shaking down the ashes.

Another object of the invention is to provide, in connection with a separator of the 35 character mentioned, an ash pan whereby the ashes may be conveniently removed from the ash pit of a furnace or stove.

Further objects of the invention will appear from the following detailed description 40 thereof.

In the drawings:

Figure 1 is a plan view of the invention;

Fig. 2 is a section on line 2—2 of Fig. 1;

Fig. 3 is an elevation of the shaker link.

Fig. 4 is a detail showing the hinged wall construction.

The numeral 1 indicates a pan suitable for receiving ashes. Said pan is adapted to fit in the ash pit of a furnace and is preferably 50 constructed of sheet metal. The front wall 2 of the pan slopes outwardly as indicated in Fig. 2 of the drawings. The pan 1 is provided with a bail 3, which is pivotally secured, as shown at 4, to the side walls 55 thereof.

A circular hopper 5 is arranged to rest on lugs 6 in the pan 1. The hopper 5 is provided with a perforated separator plate 7, which is loosely mounted for rotary motion in the hopper, being retained in position 60 therein by cross bars 8—8. Secured to the perforated plate 7 on the under side is a shaker bar 9, by means of which the plate is rotated in the hopper. Mounted in the hopper, above the plate 7 is a stationary bar 10 65 for agitating the contents of the hopper when the plate 7 is moved. The shaker bar 9 is bent as shown at 11 so as to clear the bottom of the hopper, and the outer end of the bar is provided with a flat member 12, 70 which is arranged, if desired, to receive a handle 13, shown in dotted lines in Fig. 2. The hopper 5 flares upwardly so as to be of equal dimensions with the grate bars of the furnace, and is provided with hinged side 75 walls 14, which may be turned inwardly, as shown in dotted lines in Fig. 1, so that the hopper may be inserted and removed through the ash pit door of a furnace. The lower extremities of the walls 14 are hinged 80 upon the wire which forms the bottom rim of the hopper as shown in Fig. 4.

Where the furnace is provided with grate bars agitated by rotation, the flat portion of the shaker bar 9 of the hopper may be connected with the grate shaker bar 15, by means of a bifurcated link 16, shown in detail in Fig. 3, which is provided with a head 17 arranged to be clamped to the grate bar 15. The link 16 is pivotally secured to the head 17, and the bifurcations thereof are adapted to fit against the sides of the end 12 of the shaker bar 9. Operation of the bar 15 will thus obviously cause similar action of the bar 9, separating and sifting the ashes 90 as they are received by the hopper. The pivotal mounting of the link permits the ready disengagement thereof from the shaker bar 9.

From the foregoing description the nature and operation of the present invention 100 will be apparent to those skilled in the art. By the use of the device it will be seen that the ashes may be sifted within the ash pit of the furnace or stove, thereby preventing the 105 distribution of dust and dirt about the premises as well as preventing the operator's person and garments from becoming soiled. Where the furnace is suitably constructed, furthermore, this operation may be per- 110

formed coincidentally with the shaking of the grate bars to remove the ashes therefrom. The separation having taken place, the hopper and pan may be removed and all 5 cinders suitable for fuel may be saved for such use while the ashes may be conveniently removed in the pan 1.

Having thus fully described my invention, what I claim as new and desire to secure by Letters Patent, is:

- 10 1. In combination with a furnace, a hopper arranged to be supported in said furnace under the grate bars thereof, said hopper being provided with hinged side walls 15 to permit it to pass through the ash pit door of said furnace, and means for sifting ashes in said hopper.
- 20 2. In combination with a furnace, a pan arranged to fit in the ash pit of said furnace, a hopper arranged to be supported in said pan, said hopper being provided with hinged

30 hinged side walls to permit it to pass through the ash pit door of said furnace, and means for sifting ashes in said hopper.

35 3. In combination with a furnace, a pan 25 arranged to fit in the ash pit of said furnace, a hopper arranged to be supported in said pan, means for sifting ashes in said hopper, and means whereby said sifting means may be actuated by the operation of the grate 30 bars for removing ashes therefrom.

4. In combination with a furnace, a pan arranged to fit in the ash pit of said furnace, a hopper arranged to be supported in said pan, said hopper being provided with hinged 35 side walls to permit it to pass through the ash pit door of said furnace, means for sifting ashes in said hopper, and means whereby said sifting means may be actuated by the operation of the grate bars for removing 40 ashes therefrom.

HARRY T. EMERY.
